UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

REFRIGERATING MACHINE

Application filed May 18, 1928, Serial No. 109,960. Renewed February 6, 1931.

My invention relates to refrigerating apparatus, and particularly to refrigerating machines of the type especially adapted for domestic use and an object of my invention is the provision of an improved machine of this character which shall be simple in construction, quiet and efficient in operation, durable, manufacturable at relatively low cost and have other desirable qualities which adapt it for such use.

The machine involving my invention employs a refrigerant which boils at a relatively low temperature and is caused to pass through a cycle which consists in allowing the refrigerant in the liquid form to evaporate and thus absorb heat, compressing the vaporized refrigerant, and removing the heat therefrom to cause it to condense into the liquid form again, this cycle being continuously repeated during the operation of the machine.

My invention will be better understood from the following description taken in connection with the accompanying drawings, and its scope will be pointed out in the appended claims.

Referring to the drawings, Fig. 1 is a vertical sectional view of a machine embodying my invention; Fig. 2 is a cross sectional view thereof taken on the line 2—2 of Fig. 1; Fig. 3 is an enlarged fragmentary view of Fig. 1; Fig. 4 is a cross sectional view of parts shown in Fig. 3; Fig. 5 is a fragmentary cross sectional view taken on line 5—5 of Fig. 4; Fig. 6 is a cross sectional view taken on line 6—6 of Fig. 2; Fig. 7 is a perspective view with a part broken away of the evaporator; and Fig. 8 is a perspective view of the pistons of the compressor and oil pump.

In the drawings I have shown at 1, by way of example only, the top or cover of a refrigerator cabinet such as may form a part of a domestic installation. Mounted on the top 1 is the compressor and cooling unit 2 and beneath the top and within the cabinet is the evaporator 3.

The compressor which in certain respects is similar to that disclosed in the application of Clark Orr, Ser. No. 756,336, filed Dec. 16,

1924, Patent No. 1,725,472, and assigned to the same assignee as the present application, comprises a frame 4 in which the drive shaft 5 is journalled and in which the oscillating cylinder 6 having the exhaust valve 7 is pivotally mounted by means of the trunnions 8. The moving parts are enclosed by the metal casing 9 whose lower portion is enlarged and is connected with the upper portion by the flared portion 9'. By means of lugs 10 secured to the exterior of the enlarged portion and bolts 11, the casing is held down tightly against the bottom plate 12, which plate is supported on the top 1 by the angle brackets 13. A suitable apron 14 covers this plate and the lower part of the casing to present a better appearance. Fitting in the upper portion of the casing 9 is the stator 16 of an electric motor whose rotor 17 is secured to the shaft 5. The upper edge of the frame 4 is resiliently held against the stator 16 by the pins 20 and the coil springs 21.

Surrounding the casing 9 is the condenser comprising the coil of pipe 22 whose intake 75 23 is at the top of the casing. A series of fins 24, preferably of good heat conducting material, extend radially from the casing 9 and have their outer edges provided with recesses 25 for receiving the separate turns 80 of the condenser coil 22 and making good thermal connection therewith. The inner ends of the fins are firmly secured to and in good heat conducting relation with the upper portion of the casing 9 by soldering or 85 brazing, or in any other suitable manner, and are shown, see Fig. 2, as formed in pairs each with a short connecting portion in contact with the casing. Certain of the fins are firmly secured also to the anchoring lugs 90 10, whereby they bridge the flared portion 9' and serve to stiffen the casing at this point. The fins 24 intermediate their inner and outer edges each have a row of holes 26 which, as shown in Fig. 1, is closer to the 95 outer edge than the inner edge. These holes are preferably arranged quite close together, with only sufficient material between the holes to provide necessary stiffness and mechanical strength for supporting the con- 100

- denser coil. By these fins, heat is conducted away from both the casing 9 and the condenser coil 22, the row of holes 26 forming a zero line of temperature gradient in the fins. Since in the present case the amount of heat which it is desired shall be dissipated from the casing containing the compressor and the motor is greater than that from the condenser coil, the row of holes is arranged accordingly closer to the condenser coil. By varying the relative position of the row of holes 26, it is possible to regulate to a certain extent the relative cooling effect of the fins on the casing and the condenser coil.
- 15 The fins 24, therefore, serve the triple purpose of providing a support for the condenser coil, of radiating heat from the casing, and of radiating heat from the condenser coil.
- 20 As shown in Fig. 2, the frame 4 is formed with an arcuate wall 27 forming a circular cavity centrally within which the cylinder is pivotally mounted. On the sides of the cylinder are the radial projections or fins 28, which have sliding engagement with the wall 27. Thus there is formed an exhaust chamber between the end of the cylinder and the wall 27, and two pairs of similar expansion chambers of varying size between the fins 28 and the wall 27, the chambers comprising the first pair being larger than the exhaust chamber, and the chambers comprising the second pair being larger than the first. At suitable points, the wall 27 is provided with small cut-away portions 27' which, under the control of the fins 28, permit the compressed refrigerant to pass successively from the exhaust chamber to the first and to the second expansion chambers, and then pass into the main casing. The arrangement, preferably, is such that the oscillatory movement of the cylinder following a compression stroke admits compressed refrigerant from the exhaust chamber to the two first expansion chambers, and at the same time refrigerant in the two second expansion chambers is allowed to pass into the main casing. As the cylinder oscillates in the opposite direction, and on the compression stroke, refrigerant may expand from the first expansion chambers to the second. The compressed refrigerant thereby undergoes a series of slight expansions before being delivered to the space within the casing 9, which effectually muffles the sound thereof.
- 60 The vaporized refrigerant, which is preferably sulphur dioxide, after being compressed, passes upward through the motor to the condenser intake 23. As the motor employed preferably has a very small air gap, I have provided openings 29 through the rotor 17 for the free passage of the refrigerant. These openings, as will be noted upon reference to Fig. 1, are inclined so that the

lower end is at a greater distance from the shaft than the upper end. When the rotor is in rapid rotation, any oil particles which are entrained in the compressed refrigerant will be separated out by centrifugal force as they pass through the openings and will be caused to flow downward or away from the intake 23.

70 The outlet end of the condenser coil 22 connects by the pipe 30 with casing 31 forming a float chamber 32, shown located at a rear corner of the cover 1. In this chamber is the float 33 (see Fig. 6) which, by means of the lever 34, operates the valve 35 to control the flow of liquefied refrigerant to the evaporator through pipe 36.

75 Machines of this type are designed to run intermittently in accordance with the temperature in the cabinet. The starting and stopping of the driving motor is automatically controlled and, when running, the motor is operated at relatively high speed. It is highly desirable, however, to have such a machine operate as quietly and as free from vibration as possible. I have therefore devised improved means for balancing the moving parts of my machine such that at normal running speed noise and vibration are reduced to a very low value (see Fig. 3). As stated in the beginning of the description, the compressor involves a single oscillating cylinder 6 mounted on trunnions 8 which are journaled in the frame 4. One end of the cylinder is closed by the valve 7 and projecting from the other end thereof is the piston 41 which, for the most part, is made hollow to reduce its mass. The main drive shaft 5 carries an eccentric member, shown in the present case as a crank pin 42, which is journaled in a bearing sleeve 43 carried by the piston 41. Beyond the crank pin I provide the piston with the counterweight portion 44 having such mass that the piston is substantially balanced on the crank pin whereby the center of gravity of the piston and the center of the crank pin substantially coincide. In conjunction with the above, I provide the shaft 5 with the counterweight 45 opposite the crank pin 42 and having such mass that it substantially balances the combined mass of the crank pin and the piston. In this connection, it is to be understood that the part connecting the shaft and the crank pin is considered as a part of the crank pin. As so constructed, the moving parts comprising the shaft, crank pin and piston are so balanced that even though operated at relatively high speed, but little vibration and noise are perceptible.

120 To provide adequate lubrication of the various moving parts, the cylinder and piston are partially immersed in a bath 46 of lubricating oil contained in the casing 9 from which the oil is forced to parts ar-

ranged above the bath. Referring to Figs. 4, 5 and 8, in one corner of the cylinder 6 and longitudinal thereof is the bore 47 in which slides the oil pump piston rod 48 whose outer end is fixed to the piston 41. The inner end of the bore 47 is adapted to connect by the passage 49 alternately with the passages 50 and 51 as the cylinder oscillates, whereby oil is pumped from the bath 46 to the lower trunnion bearing, to an oil groove in the cylinder wall and on up through passages 52 and 53 to the oil space 54 surrounding that portion of the drive shaft between its upper and lower bearings. Between passages 52 and 53 is the piston 55 mounted to slide in a suitable bore in the frame 4, and which is raised by oil pressure from the oil pump until the two passages connect with each other. Oil hole 56 in the shaft 5 leads from the oil chamber 54 down through the crank pin 42 to the bearing 43 therefor. A second oil hole 57 in the shaft leads from the oil chamber 54 to the spiral oil groove 57', by which oil is supplied to the thrust bearing above, from which bearing oil may freely escape through suitable grooves, and thus relieve the oil pump of excessive back pressure. It will be noted that the discharge end of the oil hole 57 is covered by the lower end of the upper shaft bearing, and that this hole from its entrance to approximately the center of the shaft is of much larger diameter than the remaining portion. This is for a definite purpose. In the case of a direct connected machine, such as that illustrated, which is adapted to run at a relatively high speed, the effect of centrifugal force on the flow of oil through the oil holes in the rotating members must be given due consideration. Should the flow of oil through the oil hole 56 leading to the crank pin, for example, become broken, the centrifugal force of oil at the entrance to this oil hole may be sufficient to prevent its entering the oil hole, since oil hole 57 provides a relatively free path of escape for the oil. However, by making the entrance portion of oil hole 57 of much larger diameter than the exit portion, and larger than hole 56, the larger mass of oil contained in the larger portion of hole 57 will prevent the flow of oil through this hole until the pressure in the oil space 54 shall have built up sufficiently to cause the oil to flow inward through this hole. Even after the oil flow is established through the holes 56 and 57, a certain predetermined pressure will be maintained in the space 54 by reason of the larger size of the entrance portion of oil hole 57, but this pressure will not rise to such a value as to impose an excessive back pressure upon the oil pump.

When the machine is restarted after an interval of rest it may happen, especially if the main piston is on the suction stroke, that the pressure in the casing acting upon the forward end of the piston is so great that starting is made difficult or even is prevented. To avoid this condition, I have provided means by which pressure is admitted to the cylinder for equalizing the pressures on the front and rear ends of the piston for the first few strokes, at least, or until the motor has had an opportunity to gain speed. In this connection, reference is had to Figs. 3 and 4. The suction pipe 58 from the evaporator, after entering the casing 9, connects with the casing 59 of the check valve 60, beyond which it connects by passage 61 with the port 62 of the compressor, thence by intake port 63 to the interior of the cylinder. Equalization of the pressure on opposite sides of the piston is effected by admitting pressure from the space within the casing 9 to the rear end of the cylinder. For this purpose, a small pipe 65 leads from the check valve casing 59 to the plate 66 covering the bore 89 where it connects with one side of the valve seat 67 formed therein, the opposite side of the valve seat connecting by the passage 68 with the interior of the casing 9. Piston 55 has mounted therein a valve 70 lightly pressed outwardly by the spring 90 so that when the piston moves upwardly under the pressure of oil, the valve 70 engages its seat while a space still exists between the piston and the plate 66. The arrangement is such that, as long as the piston is raised an amount sufficient to permit the oil to pass between passages 52 and 53, the valve 70 will be held against its seat. When the machine stops, the loss of oil pressure permits the piston 55 to descend, thus opening the valve 70 by which the pressure in the casing 9 is communicated with the intake of the compressor. If the piston is on the suction stroke, the intake ports being thus in alignment, the pressures on the two ends of the piston are equalized. This condition will continue for subsequent suction strokes until sufficient oil has been pumped to raise the piston 55 and close off the valve 70. Since the intake port 63 is spaced slightly from the end of the cylinder, I have provided the cylinder with a small opening 71 close to the end, which opening connects, when the piston is on the suction stroke, with a small opening 72 leading to the port 62.

The evaporator 3, which, as stated above, is located within the cabinet of which I have shown only the upper portion and the cover 1, in the present embodiment, is illustrated in Fig. 7 in the form of a horizontal flat plate, preferably located near the cover but spaced therefrom sufficiently to permit its being used as a shelf upon which may be placed articles to be frozen, as for example, a tray 73 for making ice cubes. The evaporator is shown comprising a rectangular cas-

ing having four side walls, a top, and a bottom, opposite side walls having lugs 75 through which extend supporting bolts 76. The bolts pass through spacing sleeves 77 and are secured into the cover 1. Inlet pipe 36 from the float valve casing 31 connects with the evaporator casing at one side thereof. The outlet or suction pipe 58 is also shown connecting with the evaporator casing at one side thereof, but its connection differs from that of the inlet pipe in that the portion 80 thereof within the casing extends to a point substantially equally distant from the four sides. The evaporator casing is intended to be only partially full of liquid refrigerant, the depth of refrigerant being about one half the depth of the casing. On the surface of the refrigerant there may be a thin layer of oil, shown for example in Fig. 1 of the drawings by the heavier shade lines, the space above the liquid refrigerant and oil being of course filled with vaporized refrigerant. The pipe 80 is shown having a goose-neck end portion 81, the open end 82 being close to the top wall of the casing, and in the curved portion are several small holes 83 some of which are located slightly above the level of the liquid refrigerant. Through these small holes 83 any oil which collects on the surface of the liquid refrigerant is slowly withdrawn. This construction avoids the necessity of exact leveling of the machine, for since the outlet is located centrally of the evaporator casing, there may be considerable deviation from exact level without affecting the relative level of the liquid at the outlet and without danger of liquid refrigerant being pumped up by the compressor.

As shown in Fig. 7, the evaporator is constructed to form a number of closed chambers 85 therein which are filled with a suitable material to constitute a heat reservoir. I provide the evaporator casing with partitions 86 which have water and gas tight connections with the walls of the casing and which form separated heat storage units lying in the liquid refrigerant. I have shown the partitions U-shaped with the two free ends let into a side wall of the evaporator casing. I construct the evaporator in an efficient and inexpensive manner by forming the sides, top and bottom of the casing and also the partitions 86 of separate sheet metal members suitably mechanically secured together and afterward copper brazing in a single operation all joints by subjecting the entire casing to treatment in a hydrogen furnace. In this manner, a plate evaporator may be constructed without the use of gaskets, with a minimum amount of material and at a small labor cost.

Through plugs 87 in the side wall to which the partitions connect, the chambers 85 formed by the partitions and wall are filled with a freezing mixture, after the casing is assembled. Various substances may be used in the chambers 85, but I prefer to use a liquid having a high specific heat and whose freezing point extends over a considerable range of temperature, such for example, as a solution of water and glycerine, or a brine solution. I use a solution such that in the normal operation of the machine a portion, at least, thereof alternately freezes and thaws, whereby the same heat storage capacity is obtainable with a smaller amount of liquid than where freezing of the liquid does not occur. In one of the chambers 85 I have shown a thermostat 88 which, by means not shown, controls the starting and stopping of the driving motor in accordance with the temperature in that chamber. By absorbing heat at one time and giving it up at another, the heat reservoir thus formed serves to produce a more even temperature in the cabinet and reduces the frequency of the operating periods of the machine. Subdivision of the heat reservoir into spaced units brings the refrigerant into closer thermal relation with the body of heat storage material, whereby a relatively small quantity only is necessary. A further advantage lies in the fact that a greater area for heat transfer is provided and the depth of the frozen solution on the walls of the units is limited by the width of the units, it being well known that by its heat insulating effect a layer of ice on the walls materially reduces the rapidity of heat transfer.

The cycle of operation of my machine, briefly, is as follows: The liquid refrigerant in the evaporator 3 is vaporized as a result of heat received from the surrounding medium. The vapor drawn up through pipe 58 by the compressor is compressed and discharged through the muffler formed at the sides of the compressor cylinder 6 into the space within the casing 9. Passing up through the inclined discharge openings 29 in the rotor of the driving motor, it enters the condensing coil 22 through the pipe 23. The compressed vapor, while in the casing 9, loses a certain amount of heat through the fins 24, and more heat is lost while it traverses the coil 22 through direct radiation therefrom and through the same fins 24. The vapor finally condenses and flows through pipe 30 into the float chamber 32, from which it escapes through float valve 35 into the evaporator 3.

Although I have shown a particular embodiment of my invention, modifications thereof will occur to those skilled in the art. I desire it to be understood, therefore, that my invention is not to be limited to the particular constructions set forth, and I intend in the appended claims to cover all modifications.

cations which do not depart from the spirit and scope of my invention.

What I claim as new and desire to secure by Letters Patent of the United States, is:

5 1. A refrigerating machine comprising a casing, a compressor therein, a condenser coil surrounding the casing and connected with the compressor, and a series of heat radiating fins on the casing for supporting the 10 condenser coil.

2. A refrigerating machine comprising a casing, a compressor and a driving motor therefor in the casing, a condenser coil surrounding the casing and connected with the 15 compressor, and a series of radial fins secured at their inner ends to the casing and having openings at their outer ends for receiving the condenser coil.

3. A refrigerating machine comprising a 20 sheet metal casing having two concentric main portions of different sizes and a connecting portion, and combined heat radiating and stiffening means for the connecting portion of the casing comprising a plurality 25 of fins in fixed connection with the two main portions of the casing.

4. A refrigerating machine comprising a sheet metal casing having two concentric main portions of different diameters and a 30 connecting flared portion, a plurality of anchoring lugs secured to the main portion of larger diameter, and a plurality of heat radiating and stiffening fins each secured to the main portion of smaller diameter and to 35 the anchoring lugs.

5. A refrigerating machine comprising a casing, a compressor therein, a condenser coil surrounding the casing, and a series of heat radiating fins on the casing and in thermal 40 connection with the condenser coil, said fins having means comprising a row of openings therein between the casing and the condenser coil forming a zero line of temperature gradient.

45 6. A refrigerating machine comprising a casing, a compressor therein, said casing having an opening for the escape of compressed refrigerant, and a motor for driving the compressor having a rotor within the 50 casing arranged between the compressor and said opening, said rotor having means therein for passing compressed refrigerant, said means being arranged to cause the separation of oil from the refrigerant during the 55 operation of the motor.

7. A refrigerating machine comprising a 60 casing having an outlet opening, a compressor in the casing, and an electric motor for driving the compressor having a rotor arranged in the casing between the compressor and the outlet opening, said rotor having openings therethrough arranged at the normal speed of the rotor to cause oil particles entrained in the compressed refrigerant 65 passing through said openings to be sepa-

rated out and to flow away from the outlet opening.

8. A refrigerating machine comprising a casing having an outlet opening adjacent the upper portion thereof, a compressor in the lower portion thereof, and an electric motor in an intermediate portion thereof for driving the compressor, said motor having its rotor provided with passages therethrough which are inclined to the axis of rotation, the lower ends of the openings being at a greater distance from the axis than the upper ends thereof.

9. A refrigerating machine having an evaporator adapted to be partially filled with refrigerant covered with a layer of lubricant, means forming an outlet passage from said evaporator having a main opening arranged above the level of the lubricant and having means forming an auxiliary outlet for affording communication with said outlet passage at different levels of the lubricant for admitting lubricant to said outlet passage upon variations in level of the lubricant in said evaporator.

10. A refrigerating machine having an evaporator adapted to be partially filled with liquid refrigerant covered with a layer of lubricant, means forming an outlet passage from said evaporator having a main opening arranged above the level of the lubricant and having a plurality of relatively small auxiliary openings arranged at different levels below said main opening and approximately at the level of the lubricant for admitting lubricant to said outlet passage upon variations of the lubricant level in said evaporator.

11. A refrigerating machine having an evaporator comprising a casing adapted to contain a liquid refrigerant said casing having a heat reservoir therein comprising a plurality of heat storage units separated by refrigerant chambers.

12. A plate evaporator comprising a casing having partitions therein forming separate chambers containing refrigerant and heat storage liquid, and a cover connected to the walls of the casing and with the partitions.

13. A plate evaporator comprising a casing built up of separate members including a top and bottom, partitions therein forming with the top and bottom separate refrigerant and heat storage chambers, and means for securing together in fluid tight relation separate members of said evaporator.

14. A refrigerating machine having a plate evaporator comprising a casing having partitions therein forming separate chambers containing refrigerant and heat storage liquid, and a cover having a brazed connection with the walls of the casing and with the partitions.

15. A refrigerating machine having a plate evaporator comprising a casing built up of separate members including a top and a bottom, and partitions therein forming with the top and the bottom separate refrigerator and heat storage chambers, said parts being secured together in a fluid-tight manner by copper brazing.
16. A mechanically operated refrigerating outfit having a chamber from which heat is to be extracted, a thin flat horizontally disposed heat absorbing unit in said chamber, and a container for liquid in thermal proximity to said unit.
17. A mechanically operated refrigerating outfit having a chamber from which heat is to be extracted, a thin flat horizontally disposed heat absorbing unit at one extremity of said chamber, and a container for liquids in thermal proximity to said unit.
18. A mechanically operated refrigerator having a chamber with walls insulated against heat, a horizontally disposed freeze plate in said chamber adjacent one extremity thereof, and a container for liquid to be frozen in contact with said plate.

In witness whereof, I have hereunto set my hand this 17th day of May 1926.

CHRISTIAN STEENSTRUP.
